Des. 225,290
Patented Dec. 5, 1972

225,290

PORTABLE STUDENT WRITING TRAY

Frank R. Torrey, 9805 Dallas Ave.,
Silver Spring, Md. 20901

Filed Feb. 19, 1971, Ser. No. 117,199

Term of patent 14 years

Int. Cl. D6—04

U.S. Cl. D6—138

FIG. 1

FIG. 2

FIG. 3

FIG. 4

FIG. 1 is a perspective view of a portable student writing tray, showing my new design;

FIG. 2 is a front elevational view thereof;

FIG. 3 is a side elevational view thereof, the other side being a mirror image thereof, and

FIG. 4 is a back view thereof.

I claim:

The ornamental design for a portable student writing tray, as shown and described.
